UNITED STATES PATENT OFFICE.

DAVID E. HUNTER, OF CAMBRIDGE, MASSACHUSETTS, ASSIGNOR TO LIBRARY BUREAU, OF BOSTON, MASSACHUSETTS, A CORPORATION OF NEW JERSEY.

EXPANSIBLE CABINET.

1,020,557.

Specification of Letters Patent. Patented Mar. 19, 1912.

Application filed September 7, 1909. Serial No. 516,530.

To all whom it may concern:

Be it known that I, DAVID E. HUNTER, a citizen of the United States, and resident of Cambridge, in the county of Middlesex and 5 State of Massachusetts, have invented new and useful Improvements in Expansible Cabinets, of which the following is a specification.

This invention relates to museum cabinets 10 and similar structures and particularly to expansible cabinets or cases of the general class known to the trade as "unit systems," by which the capacity of the cabinet or case may be varied according to the needs of the 15 user.

The invention consists in the structural peculiarities hereinafter described and particularly pointed out in the claims.

In the accompanying drawings which 20 illustrate certain embodiments of my invention,—

Figure 1 is a perspective view showing two cabinet sections and a separator in position to be assembled to make one form 25 of my improved cabinet; Fig. 2 is a front elevation of the two sections and the separator shown in Fig. 1 in assembled position; Fig. 3 is a front elevation of a modified form of cabinet sections and separator, assembled; Fig. 4 is a side elevation of one 30 of the separators used in the construction shown in Fig. 3; Fig. 5 is a vertical cross section on line 5—5 of Fig. 3; Fig. 6 is a horizontal section on line 6—6 of Fig. 3; Fig. 7 is a vertical longitudinal, central section 35 through the cabinet shown in Fig. 3, parts thereof being broken away; Fig. 8 is an enlarged detail view in section showing one of the dust-proofing strips used in 40 the cabinet shown in Figs. 3 to 6 inclusive; and Fig. 9 is an enlarged detail view in section showing one of the joints and said dust-proofing strip in compressed position between the faces of the joint.

45 Referring first to Figs. 1 and 2, A, A represent two cabinet sections which are identical in one vertical plane dimension, and as herein shown are identical in all respects. In the form herein shown the cabinets A, A are composed of panel pieces of 50 glass a, each provided with metal margin strips a', which may be separably or permanently secured together. When these cabinets are used singly or independently they 55 are inclosed by panels at all sides. To adapt

them for use in an expansible cabinet, that is, as units entering into an enlarged structure made up of similar cabinet sections, the end panels are removed so that the juxtaposed ends of two cabinet sections are open 60 and unobstructed, as shown at a².

B is a separator corresponding in contour with the identical plane contours of the cabinets A, A and consisting of a margin frame which fits between the open ends 65 of the cabinet sections, and is entirely open and unobstructed in the center as shown, whereby a clear and unobstructed space is provided through and through from one cabinet section to another when the cabinet 70 sections are assembled with the separator between them.

Each cabinet section A is mounted upon a base A' provided with a base board A². To fill the gap between the bases when two 75 cabinet sections are juxtaposed with the separator between them, the separator B is provided with the marginal depending strips or tongues B', fashioned to fit the space between the bases. Each separator B is also made with the tongue-flanges b at 80 each side to engage corresponding box-flanges a³ in the adjacent cabinet frames. Thus, when the elements are assembled as shown in Fig. 2, the separator and its depending strips make a close joint at all points between the adjacent cabinet sections and their bases. Strips of dust-proofing material such as felt may be interposed 85 if desired between the engaging joint-making faces of the cabinet frames and separator. In order to bind the cabinet sections and the intervening separator together, any suitable clamping means may be used such as the spring clips b', which may be secured to the separator B by screws, and provided with inturned ends embracing and holding the margin strips a' of the adjacent 90 panels.

Referring now to the structure shown in 100 Figs. 3 to 9 inclusive, A³, A³ represent cabinets or cabinet sections similar in general character to those shown in Figs. 1 and 2 but having their frames made of wood. Each cabinet section A³ is provided with a 105 base A⁴, the cabinets and the bases of the several sections being identical in one vertical plane dimension, as already described with respect to Figs. 1 and 2, and the cabinet sections A³ having their juxtaposed ends 110

open and unobstructed. The separator B^2 consists of a wooden margin frame adapted to fit between the ends of the walls of the cabinet sections, said frame being open and unobstructed in the center, and provided with the marginal depending strips or tongues B^3 to fill the gaps between the bases when two cabinets A^3 , A^3 are juxtaposed with a separator between them. The end 10 panels of said cabinet sections A^3 are made separable so that the cabinets may be used singly or as units in a separable system. They are removably held in place by a screw or bolt c which passes through a flange c' 15⁹ provided at the edge of the top wall of the cabinet, into the margin frame c^2 of the end panel.

In order to effect a dust-proofing joint between the ends of the cabinet sections and 20 their removable end panels, a groove or recess d is provided in one of the meeting faces of the joint, and a packing strip d' of compressible material, such as felt, is lodged therein. The packing strip d' when uncom- 25 pressed protrudes from the face of the grooved joint member as shown at d^2 (see Fig. 8). When the two joint-making faces are drawn together by the screw or bolt c (see Fig. 9) the compressible packing ma- 30 terial d^2 is compressed, effectively sealing the joint between the meeting faces. Similar dust-proofing means are used between the ends of the cabinet sections and the separator B^2 as shown in Fig. 7, save that the 35 bolt c^3 which holds the members together preferably passes completely through the two flanges c' , c' , and the separator frame B^2 , instead of terminating in the frame as shown in connection with the end panel. A 40 similar dust-proofing strip may be used for all the joints of the cabinet. Thus, as shown in Fig. 5, the dust-proofing strips d^2 are lodged in grooves in flanges e secured to the under side of the top wall of the cabinet, 45 and in grooves in the flanges e' secured to the bottom of the cabinet, said dust-proofing strips making tight joint with the frames of the side panels; and, as shown in Fig. 6, flanges e^2 , vertically arranged in the corners 50 of the cabinet, afford meeting faces for the packing strips d^2 lodged in the sides of the side panels of the cabinet. Thus it will be seen that with the inventions above set forth museum cases or cabinets may be assembled 55 from as many cabinet sections as desired, to accommodate long or short exhibits; and to

whatever extent the units may be multiplied, the interior space will be open and unobstructed from end to end.

I claim:

1. An expandible museum cabinet or case comprising a plurality of cabinet sections identical in one vertical plane dimension, the juxtaposed ends of the sections being open and unobstructed, a base for each section 60 also identical and of irregular contour in one vertical plane to permit a portion of adjacent bases to contact and provide an intervening space between the remainder of the bases and the sections, a separator between 65 adjacent cabinet sections corresponding in contour with the identical plane contours of the cabinet sections and consisting of a margin frame between the ends of the walls of the cabinet sections, said frame being open 70 and unobstructed in the center and having portions adapted to fit the space between the bases, whereby a clear and unobstructed space is provided through and through from one section to another when the sections are 75 juxtaposed with the separator between them, and means to bind said sections and their intervening separator together.

2. An expandible museum cabinet or case comprising a plurality of cabinet sections 80 identical in one vertical plane dimension, the juxtaposed ends of the sections being open and unobstructed, a separator between adjacent cabinet sections corresponding in contour with the identical plane contours of the 85 cabinet sections and consisting of a margin frame between the ends of the walls of the cabinet sections, said frame being open and unobstructed in the center, whereby a clear and unobstructed space is provided through and through from one section to another 90 when the sections are juxtaposed with the separator between them, the opposing ends of the sections having grooves or depressions, the separator having a complementary 95 tongue for each groove or depression, whereby the sections will be held against relative transverse movement by the separator, and means for removably securing the sections and separator together.

Signed by me at Boston, Massachusetts, this 31st day of August, 1909.

DAVID E. HUNTER.
